UNITED STATES PATENT OFFICE.

ROYALL D. BRADBURY, OF ANDOVER, MASSACHUSETTS.

CALIPER FOR MEASURING VARIATIONS IN LATCH NEEDLES.

Application filed December 13, 1921. Serial No. 521,973.

To all whom it may concern:

Be it known that I, ROYALL D. BRADBURY, a citizen of the United States, residing at Andover, in the county of Essex and State of Massachusetts, have invented new and useful Improvements in Calipers for Measuring Variations in Latch Needles, of which the following is a specification.

This invention relates to a new and useful improvement in calipers for measuring variations in dimensions of latch needles and consists in the novel construction and the arrangement of parts fully described in this specification, clearly illustrated in the drawings and particularly pointed out in the claims.

In the drawings like characters are used to indicate like parts wherever they occur.

Figure 1 is a perspective view showing a caliper constructed in accordance with my invention. In this view a part of the latch needle is shown in dotted lines in length-measuring position in the caliper, while the same latch needle in full lines is shown separate from the caliper in order to avoid confusion of parts.

Figure 2 shows a view of another type of latch needle from that shown in Figure 1.

Figure 3 is a view of the caliper illustrated in Figure 1 with the cover plate removed in order to show the construction and arrangement of the operating parts.

Figure 4 is a sectional view on the line 4-4 of Figure 3, showing the relative arrangement of the feed block and feed screw for the adjustable stationary pin.

Figure 5 is a vertical sectional view on the line 5-5 of Figure 3 looking in the direction of the arrow, showing the mounting of the indicating lever and its position with relation to the dial; at the bottom of the view is shown the feed block and the thumb screw for locking said block in any desired position.

Figure 6 is a side elevation showing the caliper supported for convenience on an inclined stand, the operator to be stationed at the left in said figure; this being one of the many convenient positions in which the caliper may be placed but in no way affecting its operation.

Figure 7 shows in a top plan view the mechanism for operating the indicating needle.

Figure 8 is a longitudinal sectional view 55 on the line 8-8 of Figure 7 looking in the direction of the arrow and showing the mounting of the supports for the indicator and levers.

Figure 9 is a section on the line 9-9 of 60 Figure 7, looking in the direction of the arrow, showing the mounting of the fulcrum of the lever, by which lever the indicator is operated.

Figure 10 is a sectional view on the line 65 10-10 of Figure 11, showing the construction and arrangement of the parts.

Figure 11 is a detailed perspective view of an attachment applied to the left hand end of the caliper for the purpose of comparative 70 measurements of the outside dimensions of the needle.

Figure 12 is a diagrammatic view showing a top plan of a latch needle and some of the points on the needle whose dimensions 75 are important.

The particular caliper shown by the accompanying drawings has been designed primarily for the measuring of latch needles such as are used in knitting machines for 80 the manufacture of hosiery and underwear or in fact any knitted commodity. These needles are made to very accurate dimensions and it is exceedingly important for the proper functioning of the needles when 85 placed in the knitting machines that they show a minimum variation in their important dimensions. As there are something like 200 or more needles grouped in one machine that knits one stocking, it is readily 90 seen that the problem of sorting or grouping needles according to dimensional variation does not involve merely the measuring of a few needles, but the measuring of a large quantity, probably amounting to 95 thousands.

The dial indicating caliper as shown has been devised as a new and novel means for determining the relative variation in all important dimensions for latch needles and to 100 be able to perform these operations quickly and accurately without resetting and adjusting the caliper for each needle. The caliper is really a comparative gauge as it shows instantly when a needle is in place, the amount 105 of variation in thousandths of an inch over or under the predetermined standard for which the caliper is set. One of the most

important dimensions of a latch needle is the length from the inside of the hook to the inside of the butt. With ordinary calipers or the common measuring instruments, it is impossible to read this dimension direct except by measuring over all length and subtracting widths or thicknesses which in themselves will vary.

Referring to the drawings, 1 indicates a bottom plate or base adapted to be supported by legs 2. This base is formed with a marginal flange 3, to the face of which is secured a plate or cover 4 by screws 5, the parts 1, 3 and 4 constituting a chamber or housing for the operating parts of the caliper. 6 represents a post secured to the upper face of the base 1 and having attached to its upper end a dial plate 7 by means of a screw 8. The plate 4 near its top end is cut away to form an opening 9 directly over the dial plate 7 and through which the characters on the dial can be read. This opening 9 is ordinarily protected by glass in the usual way. On the dial in the form shown the division indicates 1/1000 of an inch and the reading begins with zero in the center, running to the left under the word "Long" from zero to 20 and running to the right under the word "Short" from zero to 20, zero indicating the normal or standard length of any particular needle dimension, while the readings to the left of zero indicate lengths in excess of the standard, and the readings to the right of zero indicate lengths less than the standard.

10, Figure 3, indicates a block secured to the base 1 by a screw 11. The left hand end of this block is cut out to form forked members 12, 12, the upper forked member 12 holding an adjustable end bearing 13, while the lower forked member 12 carries a complementary adjustable end bearing 14. These bearings 13 and 14 are suitably formed upon their inner ends to receive and hold the ends of an arbor 15. 16 represents a hub or bell crank lever mounted on the body portion of the arbor 15 in the usual way. The body portion of this arbor 15 may be circular and a like opening in the hub 16 may be slid tight down on the arbor, or the body portion of the arbor 15 may be rectangular in shape to enter a like opening in the hub 16. The hub 16 is formed with two arms 17, 18, the latter or longer arm 18 serving as a pointer or indicator for the divisions on the dial 7. 20 represents a block similar to the block 10 and in like manner secured to the base 1 by a screw 21. The block 20 is formed with forked members 22, 22 carrying adjustable end bearings 23, 23^a suitably formed upon their inner ends as bearings for an arbor 24. 25 represents the hub portion of a bell crank lever arranged upon and secured to the arbor 24 in the way heretofore described or in any preferred way. The long arm 26 of this bell crank extends out from the right in Figures 3 and 7, and is arranged to rest on the under side of a pin 27 carried by the free end of the arm 17 of the bell crank 70 having the hub 16; as shown in Figure 8, the end of the arm 26 rests in a groove 28 of the pin 27. 29 represents a spring secured at one end to the flange 3 and resting at its free end in the groove 28 of the pin 27 and 75 on the top side of said pin or on the side opposite that engaged by the arm 26, the spring normally tending to force the pin 27 downward in Figures 3 and 7 and the pointer 18 to the left of the dial plate 7, 80 representing an initial or idle position, as shown in Figure 3.

The bell crank having the hub 25 carries a short arm 30, Figure 7, carrying at its free end a pintle 31, see Figure 9. This 85 pintle has a cylindrical enlargement 32 immediately above the arm 30. The base 1 carries a stationary pivot 36, upon which is mounted a hub 35 of a bell crank having two arms 38 and 34. The arm 34 is slotted at 90 its end forming two forked members 33 which are arranged on each side of the pintle 31 just above and resting upon the top of the enlargement 32 of the pintle, see Fig. 9. The other arm 38 of this bell crank is formed with a beveled face 39 adjacent the front of the caliper at the left hand side in order in the form shown to be in position to be engaged by the inner end of a movable push button 40 carried by a front plate 41 100 that is secured to the flange 3 by screws 42. The spring 29 not only normally tends to throw the pointer 18 to the left in Figure 3 in its initial position, but also yieldingly presses the arm 38 outward, together with 105 the push button 40, so that the upper end of the pintle 31, which serves as a movable measuring member 43, can be moved to the right in Figures 3 and 7 with a corresponding motion to the pointer 18. Such motion 110 of the pointer 18 and the member 43 can also be effected by the push button 40. As shown, the upper end of the pintle 31 constituting the movable measuring member 43 extends through an aperture 44 in the plate 4 of 115 sufficient size to permit the required movement of the movable measuring member. 45 represents a slot in the plate 4, in the form here shown situated slightly in front of the plane of the movable measuring member 43, 120 substantially equal to the offset distance between the point of measuring contact at the hook and a suitable measuring point of contact on the butt of the needle. This specific arrangement is advantageous for the 125 types of needles shown in the drawings, but not necessarily for all types of needles. 46 represents a screw-threaded adjusting rod supported at one end in a plate 47 carried by the upper face of the base 1, an unscrew- 130

threaded extension 48 of said rod 46 passing through a complementary aperture in the plate 47, while the extreme end of said extension 48 is provided with a washer or nut 49 to serve to hold the rod 46 in place when being turned. The other end 50 of the rod 48 has the screw threads omitted and is arranged in a complementary aperture in the plate 3 as a bearing. 51 represents a turn button secured to the end 50 by which the rod 46 can be turned. 52 represents a block formed with a central screw-threaded aperture in which the rod 46 is arranged and engaged. This block upon its upper side is formed with an extension 53 arranged in the slot 45 as a guide. 54 represents a pin carried by said extension and projecting above the surface of the plate 4 and constituting what I term an adjustable stationary measuring member. As shown, the block 52 has its side resting against the front plate 41 and its base on the base 1. 55 represents a slot in the plate 41 extending lengthwise of said plate for the distance required for the travel of the block 52. 56 represents a locking nut whose shank extends through the slot 55 and is screw-threaded into the block 52. By the described construction, the block 52 and its stationary measuring member 54 may be slid to the right or left away from or toward the member 44 and then locked in its adjusted position by the locking nut 56. 60 represents a plate formed with a slot 61, through which passes the shank of a locking nut 62. The end of this nut extends into a complementary screw-threaded aperture in the plate 4. By this construction, the plate 60 can be adjusted toward and from the slot 45, toward or from the pin of the movable measuring member 43 or toward or from the pin of the adjustable stationary measuring member 54, or any combination of these movements. The rear end of this plate is upturned to serve as a finger piece 63, by which the plate can be moved about and adjusted. The front end of this plate is extended as a finger 64 to serve as a controlling positioning member, its purpose being to so control the position of the next latch 50 needle when engaged with the two measuring members that the surfaces of the latch needles engaged by said members will enable the latter to fix and determine the distance between two surfaces of said needles notwithstanding the offset position of said surfaces. In practice, the finger 64 is positioned by either a master needle or a blank or needle known to be accurate, and locked in place. This part requires no further movement until it is desired to use some other size or style of needle as a standard of comparison. To obtain the best results in knitting machines, latch needles for a given machine or within a certain group should not 60 vary among themselves more than 3/1000 or 4/1000 of an inch, and no means prior to my invention have been available to readily grade latch needles according to these dimensions or sort them for a particular machine or job. As shown, the graduations on the dial plate 7 are in 1/1000 of an inch, running from zero in the center to the left and to the right. In the use of the machine, the pointer will be at zero only when the needle being measured agrees with a standard. If the needle being measured is shorter than the standard, the pointer will turn to the right of zero, the number of graduations corresponding to the excess of shortage, while if the needle being measured is longer than the standard, the pointer will turn to the left of zero, the number of graduations indicating the excess in length.

In Figures 10 and 11, I have shown a plate 70 formed with a slot 71, through which passes the shank of a locking nut 72, the end of said shank being arranged in a complementary screw-threaded aperture in the plate 4. The plate 70 is at its right end formed with a finger 73, the end of which constitutes a stationary adjustable measuring member. The plate 70 is formed with a depending flange 74 formed with a screw-threaded aperture in which is arranged a screw-threaded adjusting rod 75. The inner end of this rod is formed with a shaft arranged in a complementary aperture in the flange 3. A washer or nut 76 on the inner end of this rod serves to hold it from being pulled out. Beyond the flange 74 is a plate or bracket 76, the ends of which are secured in any desired way to the flange 3. This plate 76 is formed with an aperture through which the outer end of the rod 75 extends to receive a turn button 77. By the described construction, upon loosening the lock nut 72, the operator by means of the button 77 can adjust the plate 70 toward or from the measuring member 44 to any desired position corresponding to a measurement on a standard or master latch needle, after which said plate can be locked in said position by the lock nut 72.

In Figure 12, I have shown diagrammatically a latch needle 80, its butt, so-called, 81, its hook, so-called, 82, and at 83, 84, 85, 86, 87 and 88 arrows positioned to indicate points at which it is essential to know the measurements of latch needles, the measurement 83 being the one determined by measuring members 44 and 54, that being an inside measurement or caliper, while the other measurements indicated at 84, 85, 86, 87 and 88 are determined by the measuring members 70 and 44, these representing outside measurements or calipers. In making the caliper or measurement 83, the finger 64 is necessary, while in making the outside calipers referred to, the finger 64 is not used. By means of the member 64 and the posi-

tions of the members 43 and 54, the needle is necessarily so engaged by the members 43 and 54 that the distance between said members indicates or measures exactly the distance between the inner face of the hook 82 and the inner face of the butt 81 as measured on a line from the inner face of said hook substantially normally to the inner face of said butt, as indicated diagrammatically in Figure 12. By means of the pointer 18 such measurement is indicated on the dial.

In determining the length of a latch needle or the distance between the hook and the butt, the process is as follows: The locking nut 56 is loosened and by turning the button 51 the block 52 carrying with it the member 54 is moved to a distance from the member 43 equal to the said approximate length of the needle. A needle of proper length or a master needle or templet having the proper dimensions between its inside faces is then placed over the two members. With the master needle or templet thus in place, the button 51 is turned, causing the member 54 to move laterally until the member 54 engages the inner face of the hook of the master needle or templet. A continued movement of said button 51 will cause the master needle or templet to move to the right not only the member 54 but also the member 44 until the pointer 18 rests on zero of the dial. When this position is reached, the said nut 56 is tightened, thus securing the member 54 in its adjusted position. The master needle or templet is then removed and the member 43 under action of the spring 29 returns to its normal position and the pointer to its normal position. In this position, when the member 44 is pressed to the right to a point where the pointer 18 is over zero on the dial, the distance between the butt and hook of the standard needle or gauge is indicated and measured as from the outside distance of the two pins. This distance, to wit, the outside faces of the two members 44 and 54, is always a predetermined amount to which the caliper has been set.

The needle 80, see Figure 1, has its hook 82 pulled on to the member 54 and the operator by pressing the button 40 throws the member 44 to the right sufficient to let it return and engage the inside of the butt 81. The caliper is now in position ready for the measurement or comparative measurement of any number of needles, which can be quickly and easily done by simply placing the hook of the needle around the member 54, pressing on the button 40, bringing the butt of the needle around the member 44, and then allowing the member 44 to come to a bearing against the inside of the butt. The pointer will then indicate the number of thousandths of an inch by which the

needles thus positioned varies either long or short from the standard or predetermined dimension referred to.

The finger 64 being adjustable, can be moved to just the proper position so that the shank of a needle being pressed against the finger will line up so that a true, normal and not inclined measurement will be made. A needle in place for its measurement and the position of the finger 64 is indicated in Figure 1. The purpose of the finger 64 is to enable the operator to readily position the needless with reference to the position occupied by the first needle, so that attention to this point of position is not necessary on the part of the operator.

The finger 73 together with the member 44, see Figures 10 and 11, serve as a caliper for measuring the width, thickness and diameter of the hook or other dimensions of the needle, the principal ones of which are indicated in Figure 12. Such dimensions are always relatively small, and it is only necessary for the finger 72 to have a slight travel of adjustment. To measure, for instance, the width 85 of the cheek of a needle, the process is exactly similar to that described for determining the distance between the butt and the hook. The cheek of a needle having the proper width or templet is placed between the member 44 and the end of the finger 73. The button 77 is then turned and the member 44 moved until the indicator 18 stands over zero of the dial. The nut 72 is then turned, locking the plate 70, and the master needle cheek or templet is removed and the cheeks of other needles may then be placed between the finger 73 and the member 44, and the indicator will show on the dial the number of thousandths of an inch in variation in width or thickness compared with the predetermined width or thickness.

While the finger 64 serves as a convenient means for securing the proper position of the needle at the time it is being calipered having regard to the question of economy, efficiency and speed of operation, of course the positioning of the needle sufficiently accurate for all practical purposes could be secured without said finger by lining one side of said needle with relation to said slot 45 or any other mark on said plate or means of assistance. The evident difficulty, however, of attempting to locate each individual needle by eye with reference to a mark or line shows the advantage considered from the standpoint of efficiency and speed of operation of employing the finger 64 or some substantially equivalent means.

The drawings submitted show the working mechanism of the caliper and it is to be seen that by a system of levers the lateral movement of the member 44 is magnified

fifty times as compared with the movement of the pointer at the end of said lever, thus giving on the dial for a movement of the member 44 of 1/1000 of an inch a substantial and quickly readable distance.

I claim:

1. A caliper for latch needles comprising a relatively fixed member constructed and arranged to be engaged by the surface of the inner face of a latch needle hook, a complementary movable member constructed and arranged to engage the inner face of the butt of said needle, means to control the position of said needle in engagement with said members whereby the distance between said members represents the distance between the inner face of said hook and the inner face of said butt measured on a line from the inner face of said hook substantially normal to the inner face of said butt, an indicator arranged to be operated by the movable member, and means when said members are engaged by a templet or needle to adjust said templet or needle and members to bring the indicator to a zero reading without disturbing the relative positions of said members as fixed by said templet or needle.

2. A caliper for latch needles comprising a relatively fixed member constructed and arranged to be engaged by one surface of a latch needle, a complementary movable member constructed and arranged to engage another surface of said needle, a block for supporting said fixed member, an adjusting screw engaging said block for moving the latter toward and from said movable member, means for locking said block in any desired position of adjustment, an indicator arranged to be operated by the movable member whereby when said members are in proper engagement with the surfaces of any desired templet or needle the block and the two members connected by said templet or needle can be moved as a unit to adjust the indicator to a zero reading by means of the adjustment of said block and without disturbing the relative positions of said members as fixed by said templet or needle, and means to control the position of the latch needle in engagement with said members whereby the distance between said members represents the distance between the inner face of the hook of said needle and the inner

face of the butt of said needle measured on a line from the inner face of said hook substantially normal to the inner face of said butt.

3. A caliper for latch needles comprising a relatively fixed member constructed and arranged to be engaged by the surface of the inner face of a latch needle hook, a complementary movable member constructed and arranged to engage the inner face of the butt of said needle, an indicator arranged to be operated by the movable member, and means when said members are engaged by a templet or needle to adjust said templet or needle and members to bring the indicator to a zero reading without disturbing the relative positions of said members as fixed by said templet or needle.

4. A caliper for latch needles comprising a relatively fixed member constructed and arranged to be engaged by the surface of the inner face of a latch needle hook, a complementary movable member constructed and arranged to engage the inner face of the butt of said needle, means to control the position of said needle in engagement with said members whereby the distance between said members represents the distance between the inner face of said hook and the inner face of said butt measured on a line from the inner face of said hook substantially normal to the inner face of said butt, and an indicator arranged to be operated by the movable member.

5. A caliper for latch needles comprising a relatively fixed member constructed and arranged to be engaged by the surface of the inner face of a latch needle hook, a complementary movable member constructed and arranged to engage the inner face of the butt of said needle, adjustable means to control the position of said needle in engagement with said members whereby the distance between said members represents the distance between the inner face of said hook and the inner face of said butt measured on a line from the inner face of said hook substantially normal to the inner face of said butt, and an indicator arranged to be operated by the movable member.

In testimony whereof I have affixed my signature.

ROYALL D. BRADBURY.
